UNITED STATES PATENT OFFICE

2,643,665

WATER INLET SYSTEM FOR AUTOMATIC
WASHING MACHINESHarold E. Stocking, Trenton, N. J., assignor to
General Electric Company, a corporation of
New York

Application September 24, 1949, Serial No. 117,565

1 Claim. (Cl. 137—216)

1

This invention relates to an improved water inlet conduit and suds trap for washing machines.

Certain popular types of clothes washing machines have a water receptacle or tub within which is a basket in which the actual clothes washing takes place. Water for washing and rinsing, and in some cases for pre-soaking, is introduced into the tub, from which it is pumped to the basket. Plumbing codes require a free air clearance of at least one inch between the end of a water supply nozzle and the maximum overflow spill level of any vessel which may contain contaminated water, to prevent a cross-connection between the vessel and the water supply line. Accordingly, it has been the practice to conduct the water into the tub through a conduit having a funnel mouth into which the water supply pipe discharges through the required air gap.

In such washing machines soapy water centrifuged from the clothes after the washing operation passes into the tub for disposal; and in some types of machines the wash water is continuously circulated from and to the tub during the entire washing operation to filter lint and other foreign bodies from the washing solution. In either case the tub accumulates a relatively large amount of suds which tend to force their way out through any tub wall opening. This may be an annoyance in water inlet conduits of the conventional type in that suds may overflow the funnel mouth and fall to the floor, and it has been the practice to provide an ordinary U-trap at the connection of the inlet conduit with the tub, the water content of said trap preventing the outflow of suds. Where the water inlet velocity is large, however, the water discharging into the conduit will flow almost completely into the tub and an inadequate water trap remains after the water valve has been closed.

My invention has for a principal object the provision of means which will assure a proper volume of water in the suds trap, and pursuant thereto I provide a novel water inlet conduit having a U-trap characterized by a water-en-trapping chamber above a nipple or other suitable fitting discharging into the tub. Water flowing at a high velocity will enter the chamber before flowing into the tub, with the result that after the water valve has closed water remaining in the chamber will fall back into the U-trap to make up any water deficiency and establish an adequate water seal against the outflow of suds.

Other features and advantages of my invention

will be apparent from the following detailed description thereof, taken in connection with the accompanying drawing in which Fig. 1 is a partial side elevation of a washing machine embodying my invention, and Fig. 2 is a side elevation in section of the water conduit taken in section on lines 2—2 of Fig. 1.

A typical washing machine 1 includes an outer casing 2 within which is supported a water tub or receptacle 3. Within said receptacle there is contained a basket or the like (not shown) in which the clothes are washed, rinsed, and dried. As is known to those skilled in the art said basket usually contains an agitator which is oscillated by suitable motor driven mechanism, the basket then being held stationary, and when it is desired to remove water from the clothes the entire basket is rapidly spun to remove the water by centrifugal action. The extracted water passes into the tub 3 for ultimate disposition. According to the cycle of operation the water in the tub may be pumped to a discharge drain or returned to the tub. For a more complete description of such washing machines attention is directed to the pending application of Thomas T. Woodson, Serial No. 639,816, filed January 8, 1946, for "Control For Automatic Washing Machine" and now Patent 2,561,257 granted July 17, 1951, and assigned to the assignee of the present invention.

There is generally provided a water inlet system including a double valve assembly 4 for connection to the hot and cold water services of the building. Said valves contain thermostatically controlled means or equivalent for establishing a desired water temperature for the various washing functions. Ordinarily said valves are controlled by individual solenoid means 5 energized by a conventional time-cycle switch (not shown). Generally speaking, the valves individually provide hot water at about 140° F. and warm water at about 100° F. Each valve has its own nozzle or outflow conduit, the hot water valve nozzle being identified at 6, and the warm water nozzle at 7. The hot water valve may discharge into a soap dispenser (not shown) from which a mixture of hot water and soap enters the tub, or directly into the tub itself by spilling in over the top thereof as indicated in Fig. 1. The proper air gap relative to the tub may be established by a saddle clamp 8. Warm water which is used for pre-soaking and rinsing is conveyed to the tub through a conduit system which enters the tub through a side wall at the upper limit of the to-be-expected accumulation of soap suds so as to

provide means for breaking up the mass of suds which gathers about the lower portion of the basket and forms an unwanted and detrimental braking force acting to hold the tub against proper speed of rotation. The water inflow is above the normal tub water level, but because it enters the tub below its overflow spill level it is necessary to safeguard against the possibility of a cross connection between the contents of the tub and the potable water supply of the building. It is the practice to position the end of the water supply spout, for example the spout 1, at least one inch above the open end of any connection with the interior of the tub. My improved inflow conduit 9 has a funnel mouth 10 into which the water discharges from the water inlet 1 and, to prevent suds escape over the mouth, the conduit has a U-trap 11 characterized by the substantially vertical, comparatively small area, legs 12, 14. As indicated in Figs. 1 and 2 the conduit 9 may advantageously be stamped of light metal to provide a flat back wall 15 and a front wall portion 16 which provides the desired shape and cross-sectional area of the funnel mouth and leg portions. The marginal joints may be crimped and soldered for watertightness. The conduit may be affixed directly to the tub wall by self-tapping screws or equivalent 17 passing through the tub wall and into rear wall member 15. At the discharge end it is essential to have a watertight connection between the leg 14 and the tub; a suitable means comprises a rubber nipple 18 having a thickened end wall 20 grooved to receive the periphery of an opening through wall 15. A portion of the nipple wall 20 is tightly compressed against the tub wall by machine screws 21 which pass through the tub wall and are secured therein by nuts (not shown).

The present invention provides means for retaining within the trap 11 a sufficient amount of water to prevent suds escape. I have found that where water flows through the conduit 9 at high speed and directly therefrom into the tub, the water velocity will carry substantially all of the water through the trap and into the tub after the water valve is shut off. The result is that there is an inadequate amount of trap water left to provide an adequate suds block. Therefore, I make the leg 14 of the trap sufficiently long to provide a chamber 22 above the outflow connec-

tion 18. Water flowing at high velocity will initially bypass the connection 18 to strike against the end wall of the chamber, with the result that before any substantial flow enters the tub, the leg 14 is practically full. Then, when the valve 4 closes there will be sufficient water in the chamber 22 to drop into the trap and supplement the water therein to establish a suds lock of such volume and water level that the suds cannot force their way through the conduit for escape therefrom.

While I have shown a particular embodiment of my invention, it will be understood, of course, that I do not wish to be limited thereto since many modifications may be made; and I therefore contemplate by the appended claim to cover any such modifications as fall within the true spirit and scope of my invention.

What I claim as new and desire to secure by Letters Patent of the United States is:

As a new article of manufacture, a combined inlet conduit and suds trap for attachment to a tub, comprising a substantially flat backing plate for direct attachment to the side wall of said tub, said plate being generally U-shaped with one leg predominantly longer than the other and having an aperture provided in the shorter leg below the end thereof, a rounded front plate having an elevational shape corresponding to the back plate and being of coextensive length therewith, said front and back plates being secured about their common margins to provide a tubular conduit having an open end and a closed end, and a nipple having a relatively thick, deformable, end portion fitting tightly about the edge of said back plate opening and extending outwardly from said back plate to provide a flow connection between said conduit and said tub.

HAROLD E. STOCKING.
